CHARLES G. PFEIFFER, OF PHILADELPHIA, PENNSYLVANIA, ASSIGNOR TO SPECIALTY ENGINEERING COMPANY, OF PHILADELPHIA, PENNSYLVANIA, A CORPORATION OF PENNSYLVANIA.

AUXILIARY FEEDING MEANS FOR LOADING MACHINERY.

Application filed January 9, 1926. Serial No. 80,188.

This invention relates to auxiliary feeding means for loading machinery of the portable kind generally used in elevating granular or lump materials, for example, gravel, sand or coal, from a ground pile to a convenient height for subsequent gravity discharge into waiting wagons, trucks or cars. In loaders of the character referred to, an inclined endless bucket conveyor is customarily employed as the elevating means; and in use, the lower end of the conveyor is "nosed" into the ground pile of the material to enable the elevating buckets of the conveyor to take hold of it. With loading machinery as ordinarily constructed, the field of activity of the buckets is obviously confined to an area defined solely by the width of the latter, so that incidental to its operation, the position of the loader must of necessity be changed quite frequently relative to the ground pile, with consequent loss of time.

The main or underlying object of my invention is to obviate the necessity for such frequent shifting of the loader and the loss of time entailed, by increasing the working scope of the elevating conveyor. This end I attain with feeding means that cooperates, in an auxiliary capacity, to gather unto itself the material from the ground pile and to advance the same laterally, from opposite sides, into the path of the conveyor buckets so as to be scooped up by them, and elevated for the purpose previously explained.

A further object of my invention is to attain the foregoing advantage in an auxiliary feeding means of the type outlined, capable of initially breaking up or disintegrating the material—when necessary—to facilitate its progression to, and reception by, the buckets of the elevating conveyor.

With reference to the drawings, Fig. I is an illustration in side elevation—more or less diagrammatically represented—of a well known type of loading machine equipped with auxiliary feeding means conveniently embodying my invention; and,

Fig. II, is a perspective view of the front or nose end of the loader, and showing the operative relation of my auxiliary feeding means to the bucket conveyor.

The loader herein shown is of the portable type involving the use of a standard form

of gasoline tractor 5 that is relied on for 55 propulsion and actuation, said tractor being characterized by the usual rear drive wheels 6, as well as front steering wheels 7 which are controllable by the hand wheel shown at 8. The parts of the loader proper are supported by upright frames 9, 10, respectively at the rear and forward ends of the tractor 5, and include an inclined housing 11 in which an endless elevating conveyor 12 runs under support and guidance of sprocket wheels 13, 14 fast upon upper and lower shafts 15, 16. As shown, the conveyor 12 comprises a series of scooping buckets 17 designed to lift the material from a ground pile to the level of the upper sprocket shaft 15 where 70 it is dumped onto a horizontal conveyor belt 18 for progression over the top of the tractor 5, and gravity discharge, beyond the confines of the latter, in an obvious and well known manner. The horizontal conveyor 75 belt 18 runs about end pulleys 19, 20, whereof the latter is secured to a shaft 21, which, on the side of the structure remote from the observer in Fig. I, is coordinated, by means of a sprocket chain 22, with a transverse or 80 counter shaft 23 which in turn derives motion from the tractor 5 through a sprocket chain connection 24. The elevating bucket conveyor 12 is similarly driven from the shaft 21, already mentioned, by a sprocket 85 chain connection 25. In the use of the loader, the lower end of the bucket conveyor 12 is "nosed" into the pile of the material which is to be handled, to enable the buckets 17 to scoop it up in passing, and to elevate 90 it for discharge upon the horizontal conveyor belt 18 and disposal by the latter in the manner explained.

The general operation and use of the loader being now understood, I will proceed to describe, in detail, the auxiliary feeding means with which this invention is more particularly concerned. With reference to Fig. II, it will be observed that the lower sprocket shaft 16 of the bucket conveyor 100 100 has its ends extended beyond the frame bearings 27 in which it is journalled, to take the two component elements 28, 29 which jointly constitute my auxiliary feeding means. These elements are volute or spiral in form, and exact counterparts except for the fact that one is a right hand and the other a left hand spiral. In the present

instance, each of the spirals 28, 29 is shown as fabricated from sheet material, and in four sections which are collectively supported by radial arms 30 of rectangular cross section affixed at intervals to the projecting ends of the shaft 16, it being important to note that the contiguous ends of adjacent sections are secured to opposite sides of said arms. By virtue of their position in 10 the assemblages, the radial arms 30 constitute interruptions or lateral offsets in the spirals that function as hereinafter set forth. The ends of the arms 30 are extended beyond the peripheral edges of the spirals 15 28, 29, and pointed as at 31 to serve in the capacity of digging spurs.

In the operation of my improved auxiliary feeding means, the lateral offsets formed in them by the arms 30 serve as 20 paddles to gather in the material of the ground pile for lateral transfer, under the opposing action of the spirals 28, 29, into the path of the conveyor buckets 17 from opposite sides thereof. Concurrent with 25 such operation, the peripheral projections or spurs 31 afforded by the pointed ends of the arms 30, dig into the pile to loosen or disintegrate the material and thus facilitate its gathering by the offsets, as above 30 noted, for transfer by the spirals 28, 29 into the province of the conveyor buckets 17. Thus it will be seen that, by my invention, 35 the effective area of activity of the elevating conveyor 12, with regard to the ground pile, is materially increased to the end that a comparatively larger portion of the pile

is removed with each positional change of the loader as a whole, thereby obviating 40 necessity for frequent shifting of the latter incidental to a loading operation, and saving time which would otherwise be wasted.

Having thus described my invention, I claim:

1. In loading machinery of the class described, the combination of an elevating bucket-conveyor, and auxiliary feeding means comprising oppositely directed spirals on a common shaft for advancing the material to be elevated into the path of the conveyor buckets, each said spiral being composed of sections collectively supported by radial arms affording lateral transfer means with peripheral projections adapted to disintegrate the material initially.

2. In loading machinery of the class described, the combination of an elevating bucket-conveyor, and auxiliary feeding means comprising right and left hand spirals on a common shaft for advancing the material to be elevated into the path of the conveyor buckets, each said spiral comprising components collectively supported by square section radial arms, the contiguous 65 ends of adjacent sections being secured to opposite sides of said arms and thereby affording lateral transfer paddles with peripheral spur projections adapted to disintegrate the material initially.

In testimony whereof, I have hereunto signed my name at Philadelphia, Pennsylvania, this 5th day of January, 1926.

CHARLES G. PFEIFFER.
